3 Claims

ABSTRACT OF THE DISCLOSURE

A blood oxygenator of the "bubble" type including a gas bypass conduit which connects angularly disposed upper and lower sections of a gas stripping chamber arranged for downward flow of oxygenated blood to provide an escape path for undissolved gas, said gas bypass conduit being S-shaped and having opposite end openings facing downstream of the path of blood flow in the gas stripping chamber.

The present invention relates to oxygenators. More particularly, it relates to a device adapted as a substitute for a heart and lungs during surgery.

Oxygenators with which this invention is concerned are of the well-known "bubble" type adapted physically to mix oxygen with venous blood in order to effect red cell release of carbon dioxide. This is in contrast to the "film" type oxygenator adapted for mass gas transfer across a permeable barrier which is interposed between gas and liquid phases. Advantages of "bubble" type oxygenators are set out in Patent No. 3,087,490 issued Apr. 30, 1963, which together with Patent Nos. 3,058,464 and 3,112,746, respectively issued Oct. 16, 1962, and Dec. 3, 1963, discloses oxygenators for which this invention is adapted.

In addition to providing means for oxygenating blood, a "bubble" type oxygenator also necessarily has gas removal means for preventing return to the body of undissolved gases with oxygenated blood. Conventionally, the gas removal means comprises (1) a defoaming chamber adapted to liberate most undissolved gases from oxygenated blood, and (2) a stripping chamber which is arranged downstream of the defoaming chamber and is adapted for removal of the remainder of undissolved gases. Because of the requirement for removal of undissolved gases, the rate at which blood may be returned to the body after oxygenation is a function of the rate at which blood can arrive free from undissolved gas at the output end of the oxygenator.

According to the present invention, and as an object thereof, an improved "bubble" type oxygenator is provided.

It is another object of the invention to improve the efficiency of the stripping chamber of a "bubble" type oxygenator by increasing its rate of removal of undissolved gases.

Coincidentally, it is an object of the invention to improve the rate of blood flow through an oxygenator of the indicated type.

To effect the foregoing objects, a blood oxygenator has a pair of flexible faces joined together along continuous lines to provide a main conduit which has upstream and outlet ends arranged for blood flow in a downstream direction. The main conduit comprises a vertically extending oxygenating chamber, a defoaming chamber

2

which is serially connected to and disposed downstream of said oxygenating chamber, and a gas stripping chamber which is serially connected to and disposed downstream of said defoaming chamber. The stripping chamber is defined by angularly disposed upper and lower sections and a curved interconnecting section arranged for fluid communication with each other and downward flow therethrough of blood received from said defoaming chamber. Means are provided for introducing venous blood and oxygen into the upstream end of said conduit. Additionally, means are provided for venting the conduit. Furthermore, shunting means are provided for rising gas in blood downstream of the defoaming chamber, the shunting means being defined by a bypass conduit which is connected in parallel with the stripping chamber across the interconnecting section and arranged for blood flow in a direction different from the direction of flow in the main conduit to prevent trapping of rising undissolved gas in the interconnecting section.

The foregoing and other objects, features and advantages of the present invention will become more apparent upon consideration of the following description and appended claims, when considered in conjunction with the accompanying drawings wherein the same reference character or numeral refers to like or corresponding parts throughout the several views.

On the drawings:

FIG. 1 is an elevational view, partially in section, of an oxygenator embodying the present invention.

FIG. 2 is an enlarged view in section of a portion of the stripping chamber of said oxygenator showing fluid flowing therein.

Referring now more particularly to FIG. 1, there is seen an exemplary oxygenator generally designated 10 which is formed from a pair of similar translucent sheets 11 (only one of which is shown in the drawings) arranged in face-to-face lay flat relation. Sheets 11 are fabricated from a flexible polymeric material such as polyvinylchloride and united by heat seals along a number of lines 19 and 20 to form a main channel or conduit generally designated 12 and adapted for blood flow. Oxygenator 10 is equipped with a suitable horizontal upper opening for vertical suspension from a rod 13 of a hanger frame 14 to other components 15 of which the oxygenator may be secured by ties 16 (only some of which have been numbered) to secure the oxygenator in a vertical plane.

Blood to be treated is pumped into oxygenator 10 in the upstream or inlet end 17 thereof, while rejuvenated blood suitable for return to a body is removed from main conduit 12 at the downstream or outlet end 18 thereof. Blood entering upstream end 17 may come from a vein through a conduit 21 and from a wound or incision through a conduit 22. Blood entering the oxygenator through conduit 21 will not have been in contact with air, and suitable pumps (not shown) are employed to maintain such condition. The blood sucked from the wound, however, which enters conduit 22, having been contacted with air, may have clots present therein thus necessitating employment of a filter 23 which is disposed in main conduit 12 in the path of blood flow. A conduit 24 is arranged for introduction of a stream of oxygen bubbles into the upstream end 17 of main conduit 12, and a conduit 25 is arranged for removal of rejuvenated blood from the downstream end 18 of main conduit 12. Conduits 21 and 24 comprise means for introducing

venous blood and oxygen into the upstream end of main conduit 12.

Main conduit 12 comprises three serially connected chambers, namely, an oxygenating chamber 26, a defoaming chamber 27 and a gas stripping chamber 31. Oxygenating chamber 26, for which upstream end 17 comprises an entry portion at the lower end of said oxygenating chamber, extends vertically. Defoaming chamber 27 is disposed downstream of the oxygenating chamber and extends substantially horizontally from the upper end of the oxygenating chamber along the top of said oxygenator. Gas stripping chamber 31 is disposed downstream of said defoaming chamber and is defined by angularly disposed upper and lower sections 32 and 33 which are adapted for fluid communication through an interconnecting curved section 34. As shown in FIG. 1, the stripping chamber terminates in outlet end 18 and is arranged for gravity flow therethrough of blood received from defoaming chamber 27.

In the exemplary form of the invention, stainless steel sponge packing 28 occupies the defoaming chamber to provide a relatively large surface area to enhance removal of undissolved gases from blood in said chamber. A vent tube 29 connects the defoaming chamber with the exterior of the oxygenator. A similar tube 30 vents the gas stripping chamber. Tubes 29 and 30 comprise means for venting main conduit 12.

The device particularly described to this point is conventional, said device being adapted to receive and oxygenate blood in the oxygenating chamber from a patient and return the blood in rejuvenated condition to such patient from outlet end 18. However, to insure adequate blood oxygenation, excessive oxygen is introduced into main conduit 12 through conduit 24. This rises through the blood in the oxygenating chamber as undissolved gas in bubble form and causes foam formation in the blood at the top of the oxygenating chamber. Undissolved oxygen responsible for the foam, together with other undissolved gases (if any), is removed in defoaming chamber 27 in accordance with the teachings of the prior art. The defoamed blood passes from the defoaming chamber 27 downwardly through gas stripping chamber 31. It is in this latter chamber that undissolved gas not removed in the defoaming chamber rises through downwardly flowing blood for removal from conduit 12 through vent 30. To insure that all blood leaving the oxygenator through the conduit 25 is free from undissolved gas, the rate of flow of blood through the oxygenator, as well as the length of stripping chamber 31, are suitably adjusted. In this regard, it is appreciated that by increasing the stripping rate in gas stripping chamber 31, the rate at which blood may be returned to a patient from the outlet end 18 of said stripping chamber may be accordingly increased, all other factors remaining constant.

While various expedients heretofore have been employed for increasing gas stripping efficiency for the reason aforesaid, none is as efficient or effective as the invention herein disclosed. It is defined by a bypass conduit 35 which in the exemplary embodiment is S-shaped and comprises shunting means for rising undissolved gases in blood downstream of the defoaming chamber. The bypass conduit is connected in parallel with stripping chamber 31 across interconnecting section 34 and is arranged for blood flow in a direction different from the direction of flow in stripping chamber 31 to prevent undissolved gas bubbles from becoming trapped in the interconnecting section. By providing such different direction for blood flow, the flow rate in the bypass conduit is greatly decreased from the flow rate in gas stripping chamber 31, as a consequence of which blood flowing in the bypass conduit offers less resistance to rising gas bubbles than the resistance of blood flowing in stripping chamber 31. Accordingly, bubbles will rise through said bypass conduit. To effect the desired flow control of both

5 blood and undissolved gas, bypass conduit 35 has an upstream end 36 with an upper opening 37 which faces downstream in the upper angular stripping chamber section 32 through the lower wall 40 of which fluid communication is established. Moreover, bypass conduit 35 at its lower end 38 has a downstream opening 39 which faces downstream in the lower angularly disposed stripping chamber section 33 through the upper wall 41 of which fluid communication is established.

10 As a consequence of the foregoing construction, undissolved gas bubbles in lower angular section 33 will rise toward and move upwardly along upper wall 41 into downstream-facing lower opening 39 of bypass conduit 35. These bubbles will rise in the bypass conduit toward opening 37 in the direction of arrows 42 (only some of which have been numbered) against the force of blood flowing downwardly in the direction of arrows 43. The arrangement of opening 37 is such that rising bubbles are swept by the relatively rapid flow force in the stripping chamber 31 from the upper end 36 of bypass conduit 35 in the direction of arrows 45. If the opening 37 were to face upstream, escape of gas bubbles rising through the bypass would have to overcome the force of blood flow in the direction of arrows 44 in upper angular gas chamber section 32.

20 The arrangement according to the invention is such that undissolved gas bubbles are prevented from entering the curved interconnecting section 34. Instead, gas bubbles will rise from upper bypass opening 37 to the top wall 25 46 of angular stripping chamber section 32, and from there move upwardly for liberation from conduit 12. Because the improved construction facilitates removal of undissolved gases from gas stripping section 31 at a more rapid rate than the gas stripping rate of heretofore known "bubble" type oxygenators, the blood flow rate through an oxygenator in accordance with the present invention may be increased over the rate of flow in oxygenators of like size constructed in accordance with the prior art.

What is claimed is:

1. In a blood oxygenator of the "bubble" type having a pair of flexible faces joined together along continuous lines to provide a main conduit having upstream and outlet ends arranged for blood flow in a downstream direction, said main conduit comprising a vertically extending oxygenating chamber, a defoaming chamber serially connected to and disposed downstream of said oxygenating chamber, and a gas stripping chamber serially connected to and disposed downstream of said defoaming chamber, said stripping chamber defined by angularly disposed upper and lower sections and an interconnecting curved section arranged for fluid communication with each other and downward flow therethrough of blood received from said defoaming chamber; means for introducing venous blood and oxygen into the upstream end of said main conduit, and means for venting said conduit, the improvement comprising shunting means for rising undissolved gas in blood in said angularly disposed lower section and defined by a bypass conduit connected in parallel with said gas stripping chamber across said interconnecting section, said bypass conduit having an upstream end with a downstream-facing opening in the upper of said angularly disposed sections to facilitate transfer of bubbles from the lower to the upper of said angularly disposed sections to provide blood flow in said bypass conduit at a rate different from the rate of flow in said gas stripping chamber, to prevent trapping of rising undissolved gas in said interconnecting section.

2. A combination according to claim 1 in which the bypass conduit has a downstream end with a downstream-facing opening in the lower of said angularly disposed sections to facilitate entry of undissolved gas from downstream of said last opening into said bypass conduit.

3. A combination according to claim 1 in which each of said angularly disposed sections has upper and lower walls, said bypass conduit being S-shaped with opposite

3,502,440

5

end openings arranged for fluid association with said angularly disposed sections through the lower wall of the upper section and the upper wall of the lower section.
